INTERNAL COMBUSTION MOTOR

Frank K. Shear, Ravana, N. Y.

Application November 17, 1933, Serial No. 698,508

1. Claim. (Cl. 123—75)

This invention relates to an internal combustion motor, the general object of the invention being to provide means whereby the motor will operate with the minimum amount of fuel.

5 This invention also consists in certain other features of construction and in the combination and arrangement of the several parts, to be hereinafter fully described, illustrated in the accompanying drawings and specifically pointed out in 10 the appended claim.

In describing the invention in detail, reference will be had to the accompanying drawings wherein like characters denote like or corresponding parts throughout the several views, and in 15 which:—

Figure 1 is an elevation of an engine constructed in accordance with this invention.

Figure 2 is an end view of the invention.

Figure 3 is a longitudinal sectional view through 20 the improved engine.

Figure 4 is a top plan view.

Figure 5 is a fragmentary view of the cam shaft.

In these drawings, the numeral 1 indicates the cylinder block which is shown as being provided 25 with a single cylinder 2, but it will, of course, be understood that as many cylinders can be provided as desired. The crank case is shown at 3, containing the crank shaft 4, the crank of which is connected by the rod 5 with the piston 6 in the 30 cylinder 2. The head is shown at 7 and both the block and the head are provided with the water jackets 8, though it will, of course, be understood that the engine might be air cooled, if desired. The head forms a chamber 9 at the upper end of 35 the cylinder and at one side of the engine, this chamber is in communication with the exhaust 10 controlled by a valve 11 normally held closed by the usual spring 12 and which is opened by the push rod 13 operated by the cam 14 on the 40 shaft 15 which is driven from the crank shaft by the means shown generally at 16.

The head is formed with a substantially dome-shaped part 17 which forms a fuel chamber 18 and has a threaded opening in its top for receiving the spark plug 19. The chamber 18, as will be seen, is of cylindrical shape with a concave top and has its lower end opening out into the chamber 9 and said chamber 18 is of much less diameter than the cylinder 2 and is located above 50 the central part of said cylinder 2.

An air conduit 20 is in communication with that part of the chamber 9 which is directly opposite the part in communication with the exhaust 10 and communication between the conduit and the chamber 9 is controlled by a valve

21 normally held closed by a spring 22 and which is opened by a push rod 23 operated by a cam 24 on a shaft 25 rotated from the crank shaft by the means shown generally at 26.

A conduit 27 has one end in communication with the fuel chamber 18 and its other end is adapted to be connected to a carburetor or the like and the passage of the fuel through the conduit 27 is controlled by a spring pressed valve 28 operated by a push rod 29 actuated by a cam 30 10 on the shaft 25.

A short conduit 31 connects the air conduit 20 with the fuel conduit 27 and a manually operated valve 32 is located at the lower end of said conduit 31. This valve is so located and arranged 15 that in one position it will close the air conduit and in its other position it will close the conduit 31.

The principle of operation is as follows:—

On the down stroke of the piston 6, the valve 20 21 opens so that air flows into the cylinder and chamber 9 from the conduit 20, all of the other valves, including the valve 32, being closed. When the piston has reached a certain point in its downward stroke, the valve 21 will close and 25 simultaneously the fuel valve 28 will open so that during the rest of the downward motion of the piston 6, fuel will be drawn through the conduit 27 into the fuel chamber 18. The exact point in the descent of the piston where the valve 21 will 30 close and the valve 28 will open will vary in different makes and types of engines. However, the opening and closing of the two valves occur simultaneously. On the upward stroke of the piston, the air in the cylinder, acting as a cushion, forces the fuel to the top of the gas chamber 18, directly under the spark plug, where it is exploded. Just enough fuel is drawn into the fuel chamber 18 to actually operate the engine, the remaining space being filled with air. This 40 makes the engine very economical as to the use of fuel and lessens the cost of operation.

As will be seen, the air and gas mixture is not mixed in the cylinder as the air is first drawn into the cylinder and then the air supply closed 45 and then the gas mixture is drawn into the chamber 18. On the compression stroke, the air in the cylinder acts as a cushion against the gas mixture in the chamber 18 so that the gas mixture is forced by the pressure of the air to the top of the chamber 18 where the explosion takes place. The air is used for the purpose of giving the necessary compression on the compression stroke without first filling the cylinder with the fuel mixture.

At the beginning of the engine operation, the valve 32 is moved to a position to extend across the air conduit 20, so that some of the gas mixture will pass through the short conduit 31 into the air conduit and then into the chamber 9 and cylinder 2 to provide a rich mixture for the starting of the engine. Thus only the fuel mixture is drawn into the cylinder and chamber 18, as the flow of air through the conduit 20 is prevented by the valve 32. After the engine has started, the valve 32 is moved to its other position to close the conduit 31 so only air will enter the cylinder for the first part of the suction stroke.

It is thought from the foregoing description that the advantages and novel features of the invention will be readily apparent.

It is to be understood that changes may be made in the construction and in the combination and arrangement of the several parts, provided that such changes fall within the scope of the appended claim.

What is claimed is:—

In an internal combustion engine including a cylinder and a piston and a head for the cylinder having a fuel chamber therein in commun-

cation with the cylinder, an air supply connected with the outer end of the cylinder, a fuel supply connected with the fuel chamber, valves for controlling said supply, springs for normally holding the valves closed, means for opening the air valve at the beginning of the suction stroke of the piston and permitting the valve to close when the piston reaches a certain point in its suction stroke, means for simultaneously opening the fuel valve as the air valve is closing, whereby air is drawn into the cylinder at the beginning of the suction stroke and fuel is drawn into the fuel chamber for the rest of the stroke after the air valve is closed, said air being compressed by the piston on its compression stroke, the pressure of air compressing the fuel in the fuel chamber, means for firing the fuel in said chamber, a short conduit connecting the air conduit with the fuel conduit, and a valve for closing said short conduit when the valve is in one position and said valve closing the air conduit and placing the short conduit in communication with the air conduit when in another position.

FRANK K. SHEAR. 25
